UNITED STATES PATENT OFFICE

147,717

DESIGN FOR A TOY TRACTOR

William G. Borders, Bell, Calif.

Application February 25, 1946, Serial No. 126,876

Term of patent 3½ years

(Cl. D34—15)

To all whom it may concern:

Be it known that I, William G. Borders, a citizen of the United States, residing at Bell, in the county of Los Angeles and State of California, have invented a new, original, and ornamental Design for Toy Tractor, of which the following is a specification, reference being had to the accompanying drawing, forming part thereof.

The drawing illustrates a toy tractor embodying my new design in which

Fig. 1 is a side elevational view;

Fig. 2 is a front elevational view;

Fig. 3 is a rear elevational view; and

Fig. 4 is a top plan view.

I claim:

The ornamental design for a toy tractor, as shown.

WILLIAM G. BORDERS.
